AMMONIA FORCE-FEED REFRIGERATING SYSTEM.

1,106,244.

Specification of Letters Patent.

Patented Aug. 4, 1914.

Application filed January 25, 1911, Serial No. 604,631. Renewed September 18, 1913. Serial No. 790,569.

To all whom it may concern:

Be it known that I, WILLIAM SCHLIEMANN, a citizen of the United States, residing in the city of Washington and District 5 of Columbia, have invented new and useful Improvements in Ammonia Force-Feed Refrigerating Systems, of which the following is a specification.

This invention relates to certain new and 10 useful improvements in force feed refrigerating apparatus, of which the following is a full, clear and exact description.

The primary object of the invention is to provide a refrigerating system embodying a flooded force feed apparatus in which the refrigerant liquid will be prevented from going to the compressor; and the coils are kept flooded with the refrigerant liquid.

The advantages of the system consist in 20 the great saving of time and labor, and in the high efficiency easily to be obtained, both in the compressor and the refrigerating coils, as the apparatus is practically automatic after once having been set into 25 operation.

Other objects and advantages will be fully explained in the following description and claims.

Reference will be had to the accompanying 30 diagrammatical drawing forming a part of this specification.

Reference numeral 1 designates the refrigerating tank containing the usual expansion coil 2, the same being of any approved type as used in the manufacture of 35 artificial ice, or in cooling systems generally. The inlet end of the expansion coil is shown provided with the expansion valve 3 common in expansion systems, but this 40 not being essential in this system is illustrated merely to illustrate the adaptability of this invention to the expansion system without radical change in the latter. The normal position of this valve in the present 45 invention is open.

Feeding into the inlet end of the coil 2 is the refrigerant liquid feed pipe 4, leading from the condenser 5 and compressor 6, both of any approved type. Of course it will be 50 understood that in lieu of the compressor and condenser, any other apparatus may be employed that is capable of serving the functions thereof. Located in the feed pipe 4, is a refrigerant liquid feed-valve 7 for

regulating the feed of the liquid refrigerant 55 to the evaporating coil. Obviously, instead of one of such coils, a plurality thereof may be employed, in which case, inlet and outlet headers 8 and 9 respectively are provided, there being a reducing valve 3 for each coil, 60 if desired.

Indicators 10 and 11 are provided on opposite sides of the feed valve 7 for indicating pressures respectively in the supply pipe 4 and in the expansion coil. 65

The refrigerant liquid, after accomplishing its work in the expansion coil or coils 2, is led therefrom, in the form of liquid and gas, by pipe 12; the formation of gas in the coils being due to the evaporation 70 of the refrigerant liquid therein. This pipe 12 discharges into a separator 14 which may be of any approved type, and is equipped with pressure indicator 15 and gage glass 16. The difference between 11 and 15 75 shows the pressure differential between the inlet and outlet of the coil; a differential which may be variably adjusted by control of valve 27. From the separator, the gas is taken through the pipe 17 leading to the 80 suction end of the compressor or absorber, and after compression the gas is piped to the condenser 5, from which it is returned in the form of refrigerant liquid to the evaporating coil or coils 2. From the separator, 85 the separated refrigerant liquid is collected by a pipe 20 tapped into the lower end thereof and equipped with a valve 21. The pipe 20 leads to a point (shown as just above a floor 22) below its discharge 90 end, and is then brought upwardly thereby forming a trap or liquid seal 23. The discharge end 24 enters a mixing chamber or gas reliever 25, and may be bent upward 95 therein to direct the entering liquid to facilitate any gas that might be contained in the liquid rising to the upper portion of said chamber, from whence it is led off by pipe 26, equipped with valve 27, and entering the discharge end of the evaporating 100 coil 2. Pipe 26 establishes gas communication between 25 and the outlet of the coil. By adjustment of 27 the difference in pressure indicated by 11 and 15 may be adjusted.

The gas flowing through said pipe 105 or equalizing conduit 26, will mingle with the gas in the discharge pipe 12 and pass on to the separator 14 as already described.

It is not essential that the pipe 26 discharge directly into the pipe 12 so long as some means is provided establishing controllable gas communication between the body of refrigerant in 25 and the means beyond the coil, whereby the gas therefrom is returned to the compressor or absorber 6. The lower end of the mixing chamber or gas reliever directly connects the inlet end of the expansion coil with feed pipe 4, in such manner that any non-condensed gas coming through pipe 4, instead of entering the coil 2, will pass up into the chamber or gas reliever 25 to be carried off by said pipe 26 which is provided with valve 27. The liquid from pipe 20 passes into the inlet end of the expansion coil together with the liquid from pipe 4 and in such proportions as the adjustment of the valve 7 allows. The liquid refrigerant comes from the condenser with a high pressure and temperature. When it enters 24 and is reduced to the low pressure needed in the refrigerating coils, a great part (with ammonia about $\frac{1}{2}$) is evaporated as the liquid cools to the temperature corresponding with the lower pressure in the refrigerating coils. This gas is carried off by the pipe 26 instead of going through the expansion coils and causing an irregular flow and hammering therein. The leg 23 forms a trap or liquid seal, and prevents the gas, before its passage from the chamber or reliever 25, from entering the pipe 20. The lubricating oil, from the compressor or other machinery, which collects in the apparatus and at times is in considerable amount, is separated in the separator 14 together with the refrigerant liquid, and being of greater specific gravity than the refrigerant liquid, occupies a lower stratum in the gage-glass 16 than the refrigerant liquid. This oil is led off from the separator by means of pipe 29 equipped with an oil separator or settling chamber 30 having a discharge valve 31. It will be observed that the upper end of the pipe 20 extends upwardly slightly into the separator to prevent the lubricating oil in the bottom of the separator 14 from entering said pipe. During the passage of the refrigerant liquid through the expansion coils, it becomes partly evaporated, forming a mixture of gas and liquid; and these two elements pass into the separator 14 and are separated, the gas flowing to the compressor or absorber and the separated liquid returning to the expansion coils from the separator by way of pipe 20 and mixing chamber or gas reliever 25. Any gas present in the gas reliever 25 is carried off to the separator by pipe 26. Until a pre-determined amount of liquid accumulates in the separator, the valve 21 and preferably also the valve 27 remain closed, so that a suitable pressure may be first

established in the chamber 25 to start the circulating movement. When this movement has begun the said valves are opened, so as to return the liquid automatically to the inlet end and the refrigerating coil. The opening of the valve 27 provides further removal of gas accumulating in the chamber 25 so that (first) such gas may be kept from passing through the expansion coil and consequent hammering avoided; (second) so that a substantial equality of pressure differential will prevail between the inlet and outlet end of the expansion coil or coils, thus insuring uniform and regular progress of the refrigerant therethrough, and (third) so that the necessity of precooling the incoming liquid from the condensers may be avoided. It will be evident that by adjustment of the valve 27, *i.e.*, a restriction of the communication it affords between inlet and outlet of the expansion coil, the pressure in the chamber 25 may be increased to increase the flow of refrigerant and thereby accommodate an increasing load on the system. The valve 27 is thus a controlling member for the system.

Any refrigerating agent may be used that is capable of liquefaction or gasification.

I claim as new:

1. In a refrigerating apparatus, a refrigerant liquid supply pipe, an expansion coil, a refrigerant gas discharge pipe, a refrigerant liquid and gas separator connected to the discharge pipe, means for returning the separated liquid from the separator to the inlet end of the expansion coil, and a gas reliever intermediate the said means and the inlet end of the expansion coil.

2. In a refrigerating apparatus, a refrigerant liquid supply pipe, an expansion coil, a refrigerant gas discharge pipe, a refrigerant liquid and gas separator connected to the discharge pipe, means for returning the separated liquid from the separator to the expansion coil, a gas reliever included in said means, and gas discharge connection between said reliever and said discharge pipe.

3. In a refrigerating apparatus, a refrigerant liquid supply pipe, an expansion coil, a refrigerant gas discharge pipe, a refrigerant liquid and gas separator connected to the discharge pipe, means for returning the separated liquid from the separator to the expansion coil, a gas reliever intermediate the said means and the inlet end of the expansion coil, and means whereby the gas is led from the reliever into the discharge pipe.

4. In a refrigerating apparatus, a refrigerant liquid supply pipe, an expansion coil, a refrigerant gas discharge pipe, a refrigerant liquid and gas separator connected to the discharge pipe, means for returning the separated liquid from the separator to the

- expansion coil, a gas reliever intermediate the said means and the inlet end of the expansion coil, and a liquid seal included in said means.
- 5 5. In a refrigerating apparatus, a refrigerant liquid supply pipe, an expansion coil, a refrigerant gas discharge pipe, a refrigerant liquid and gas separator connected to the discharge pipe, means for returning the 45 separated liquid from the separator to the expansion coil, and a gas reliever intermediate the said means and the expansion coil, means for returning the separated liquid from the separator to the expansion coil, and a gas reliever intermediate the said means and the expansion coil, said returning means discharging into said gas reliever.
- 10 6. In a refrigerating apparatus, a refrigerant liquid supply pipe, an expansion coil, a refrigerant gas discharge pipe, a refrigerant liquid and gas separator connected to the discharge pipe, means for returning the 50 separated liquid from the separator to the expansion coil, a gas reliever intermediate said means and the refrigerating coil, said means discharging upwardly into the gas reliever, and a liquid seal located in said 55 means.
- 15 7. In a refrigerating apparatus, a refrigerant liquid supply pipe, an expansion coil, a refrigerant gas discharge pipe, a refrigerant liquid and gas separator connected to the discharge pipe, and means including a liquid seal for returning the separated liquid to the expansion coil.
- 20 8. In a refrigerating apparatus, a refrigerant liquid supply pipe, an expansion coil, a refrigerant gas discharge pipe, a refrigerant liquid and gas separator connected to the discharge pipe, a feed valve for the inlet end of the expansion coil, and means including a liquid seal for returning the separated liquid to the expansion coil.
- 25 9. In a refrigerating apparatus, a conduit for refrigerant liquid, an expansion coil, an intermediate liquid reservoir, a separator for liquid and gas beyond the expansion coil, suction means beyond the separator, means for returning liquid from the separator to the reservoir and a valved equalizing pipe establishing gas communication between the reservoir and the elements beyond the expansion coil.
- 30 10. In a refrigerating apparatus, a conduit for refrigerant liquid, an expansion coil, means for supplying liquid refrigerant thereto, means for withdrawing liquid and gaseous refrigerant therefrom and returning said liquid to said supplying means, and a valved equalizing conduit establishing gas communication between said supplying and said withdrawing means.
- 35 11. In a refrigerating apparatus, a conduit for refrigerant liquid, an expansion coil, means for supplying liquid refrigerant thereto, means for removing liquid and gas therefrom and for returning liquid to the supplying means and valve controlled means for passing gas from said supplying 65 means to said removing means past said coil.
- 40 12. In a refrigerating apparatus, a conduit for refrigerant liquid, an expansion coil, means for supplying liquid refrigerant thereto, means for removing liquid and gas therefrom and for returning liquid to the supplying means and an equalizing pipe for passing gas from said supplying means to said removing means past said coil.
- In testimony whereof I have hereunto set my hand in presence of two subscribing witnesses.
